UNITED STATES PATENT OFFICE.

ISIDORE MARKS, OF BOSTON, MASSACHUSETTS, ASSIGNOR TO KEYSTONE MANUFACTURING COMPANY, OF BOSTON, MASSACHUSETTS, A CORPORATION OF MASSACHUSETTS.

MOTION-PICTURE MACHINE.

1,345,793.

Specification of Letters Patent.

Patented July 6, 1920.

Application filed October 17, 1919. Serial No. 331,297.

To all whom it may concern:

Be it known that I, ISIDORE MARKS, a citizen of the United States, residing at Dorchester, Boston, in the county of Suffolk and 5 State of Massachusetts, have invented certain new and useful Improvements in Motion-Picture Machines; and I do hereby declare the following to be a full, clear, and exact description of the invention, such as 10 will enable others skilled in the art to which it appertains to make and use the same.

This invention relates to motion picture machines and more particularly to such machines for family use in the home generally designated as toys.

The object of the present invention is to improve the construction of such apparatus and increase its efficiency of operation, with 20 simplicity of parts, cheapness of manufacture and ready adjustability. Accordingly an important feature of the invention comprises a novel and efficient method of cooling the light box; and a further feature comprises provision for adjusting the light, of 25 whatever size, to the most efficient position relative to the reflector and lenses.

To the accomplishment of the above object and such others as may be hereinafter appear, as will readily be understood by 30 those skilled in the art from the following description, the invention comprises the features and combination of parts hereinafter described and then pointed out in detail in the appended claims.

35 In the accompanying drawings, showing the preferred form of the invention, Figure 1 is a side elevation of the complete machine, and Fig. 2 is a vertical section through the center of the light box, from front to rear.

In the embodiment of the invention illustrated in the drawings the machine is supported on a base block 2, which may be of wood, and is composed of two wholly separate parts, namely a light box for and a film supporting and feeding frame 6.

It will be unnecessary to describe in detail the parts carried by the frame 6 since this portion of the machine is, in general, similar to prior machines and not a part of the present invention. It will suffice to say that the frame 6 is channel shaped having a horizontal shaft journaled in its side flanges, provided with a crank 8 on one end and a

balance wheel 10 on the other. Gears are 55 provided as shown in Fig. 1 for operating a Geneva stop motion which intermittently advances the usual toothed feed drum carried centrally on the shaft below the projecting lens holder 12. The film used is 60 endless, running over a freely revolving reel 14, sustained on wire supports 16 rising from the frame 6, and then downward through a passage behind the hinged door 18 which holds it in contact with the feed 65 drum.

The features of the present invention relate to improvements in the construction of the light box 4, which, it will be observed, is wholly inclosed and removed from the 70 film carrying frame thus overcoming danger of the heat destroying the film or causing a fire. To further guard against overheating, the box is so constructed as to provide for an efficient circulation of cool air. To 75 this end the light box which, as shown, comprises front and side walls 20 and 22 respectively and a cover 24 of sheet metal, is provided with a removable or sliding back 26. The cover 24 is shortened, leaving an opening 80 from side to side 25 at its rear end, and the back is provided with a forwardly curved open ended hood 27 which spans the opening 25. The back also is shortened and does not reach to the base block 2 leaving an 85 opening 28. The side edges of the back are folded on themselves to embrace outwardly turned flanges 23 on the rear edges of the sides 22 permitting the back to be slid upwardly on said flanges and thus removed to 90 gain access to parts within the box. Within the light box is a block 30, secured to the block 2, to which the box is fastened. The block 30 is not as long as the light box is deep leaving a space 31 between it and the 95 opening 28. With this construction the cool air will enter the opening 28, be deflected upward by the rear end of the block 30, and finally pass out through the space 25, and open ends of the hood 27.

The cover 24 is provided with a central opening 32 through which the socket 33, which carries the bulb 34 is introduced. The socket is provided with a tubular light-wire holding stem 35 which is adjustably secured 105 to a sustaining bell 36 resting on the cover 24 and closing the opening 32. The adjustment is secured through a set screw 37

threaded through a collar 38 carried on the bell. This adjustment is important in regulating the vertical position of bulbs of different sizes relative to the reflector 40 and 5 lens 42 secured to the back and front wall, respectively, of the light box.

The nature and scope of the present invention having been indicated and the preferred embodiment thereof having been 10 specifically described, what is claimed as new, is:—

1. A light box for motion picture machines having front and side walls, a cover shorter than the side walls forming an opening 15 at its rear end, an open ended hood covering said opening and a back having an opening at its lower end.

2. A light box for motion picture machines comprising a base block, walls rising 20 therefrom including a vertically sliding back provided with a forwardly curving hood at its upper end, and a cover the rear

edge of which lies just under the forward edge of said hood, said back being of such length as not to reach the base block when 25 its hood contacts with the cover.

3. A light-box for motion picture machines comprising front, side and top walls and a base, the front wall being provided with a light-emitting opening, said top wall 30 terminating short of the rear edge of the box to form a transversely-extending air-exit, a light member inclosed in the box, a back wall provided with a reflector, said back wall being slidably mounted on the 35 side walls and having its top edge bent forwardly and downwardly to meet the upper face of the top wall to thereby form an open-ended hood extending across the top of the box over said air-exit, the bottom 40 edge of said back wall terminating short of the base to thereby provide an air-inlet extending across the rear side of the box.

ISIDORE MARKS.
